(57) **CLAIM**

We claim the ornamental design for a multiple fuse holder, as shown and described.

DESCRIPTION

FIG. 1 is left-front perspective view of a first embodiment showing our new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear elevation view thereof;

FIG. 7 is a front elevation view thereof;

FIG. 8 is left-front perspective view of a second embodiment showing our new design;

FIG. 9 is a top plan view thereof;

FIG. 10 is a bottom plan view thereof;

FIG. 11 is a left side elevation view thereof;

FIG. 12 is a right side elevation view thereof;

FIG. 13 is a rear elevation view thereof; and,

FIG. 14 is a front elevation view thereof.

The broken line showing of the environment is for illustrative purpose only and forms no part of the claimed design.
